(57) **CLAIM**

The ornamental design for a pantyhose having a gradation of a greater to a lesser amount of color, as shown and described.

DESCRIPTION

FIG. 1 is a perspective view of a pantyhose having a gradation of a greater to a lesser amount of color, showing my new design;

FIG. 2 is a front elevational view thereof;

FIG. 3 is a rear elevational view thereof;

FIG. 4 is a side elevational view of the right side thereof, with the left side being a mirror image of the right side;

FIG. 5 is a top plan view thereof; and,

FIG. 6 is a bottom plan view thereof.
